FIGURE 1 is a top view of an outdoor telephone booth showing my new design;

FIGURE 2 is a front elevational view thereof;

FIGURE 3 is a plan view thereof taken along the line 3—3 of FIGURE 2; and

FIGURE 4 is a plan view thereof taken upwardly along line 4—4 of FIGURE 2.

The base of my design is essentially plain and unornamented.

The broken lines shown in the drawing are disclosed for illustrative purposes only.

I claim:

The ornamental design for an outdoor telephone booth, as shown and described.
